UNITED STATES PATENT OFFICE.

GEORGE S. OLSON, OF SWIFT CURRENT, SASKATCHEWAN, CANADA.

HASP.

1,377,426.

Specification of Letters Patent. Patented May 10, 1921.

Application filed June 11, 1920. Serial No. 388,100.

To all whom it may concern:

Be it known that I, GEORGE S. OLSON, a subject of the King of Great Britain, residing at Swift Current, in the Province of 5 Saskatchewan, and Dominion of Canada, have invented certain new and useful Improvements in Hasps, of which the following is a specification.

This invention relates to new and useful 10 improvements in hasps, the primary object of the invention being to provide a double lock therefor, whereby the closure to which the hasp is applied may be securely retained in a closed position.

15 Another object of the invention is to provide a hasp including a plurality of hingedly connected sections, whereby they may execute proper movement to be associated with a locking element.

20 Another object of the invention is to provide a locking element having means to engage the hasp at two points whereby the latter may be securely retained in a locked position.

25 Still another important object of the invention is to provide a device comprising in combination, a hasp and a pair of locking members adapted for either joint or separate co-operation with the hasp whereby the 30 hasp may be locked or merely engaged by one of the locking members for temporarily hooking the hasp, for example, similar to the hooking of a screen door with the well known hook and eyelet.

35 Other objects and advantages of the invention will become apparent during the course of the following description.

In the accompanying drawings forming a part of the application and wherein like 40 numerals are employed to designate like parts throughout the several views,

Figure 1 is a top plan of the invention applied to a door and its frame.

Fig. 2 is a top plan of the invention in a 45 folded condition, parts of the invention being broken away.

Fig. 3 is a side elevation of my improved hasp, and

50 Fig. 4 is a side elevation of my improved locking element.

Referring to the drawings wherein for the purpose of illustration is shown the preferred embodiment of the invention, the 55 numeral 5 designates a portion of a door, in the present instance, the free edge of which is adapted to abut with a door frame 6.

My improved hasp in the present instance is illustrated as consisting of three sections pivotally connected together, one end section 7 forming an anchor plate and adapted to 60 be secured to a door frame, an intermediate section 8 and an end locking plate or section 9. The anchor section 7 is equipped with a plurality of apertures whereby screws may extend therethrough for securing the 65 plate to the door frame. The contiguous ends of the sections are formed with the well known knuckles 10 and pintles 11 extend through the co-operating knuckles for hinging the sections together. It is 70 to be particularly noted that the end of the section 8 adjacent the locking section 9 is provided with a pair of spaced knuckles 12 and the cut out portion 13 between these knuckles is extended farther inwardly of 75 the intermediate plate 8 than usual, so that when the knuckle 14 of the locking plate is disposed in its co-operative position between the knuckles 12, a slot or aperture 15 is provided in the plate 8, as the knuckle 14 of the 80 locking plate closes the open end of the cut out portion 13. The usual elongated slot or aperture 16 is provided in the locking plate 9 adjacent its free end for the well known purpose. Due to the hinging of the hasp 85 sections, it will be apparent that the sections 8 and 9 are capable of moving outwardly of the door frame 6. A locking element or plate 17 is secured to the door in the well known manner and the end of the 90 locking element remote from the door frame is provided with the well known form of staple 18 which is adapted to extend through the slot 16 of the hasp when the latter is swung to a locked position. The 95 opposite end of the locking element is equipped with a laterally projecting curved extension 19, the free end of which is adapted to extend through the opening or aperture 15 in the intermediate hasp section 100 and overlap a portion of the hinge connection between the sections 8 and 9 when the hasp is disposed in a locked position. In this manner, it will be apparent that the locking plate 9 is locked in engagement 105 with the door at two points, one being adjacent the end of the door which abuts with the frame, while the other is slightly remote therefrom.

In use, and assuming the device applied 110 in the manner illustrated in Fig. 1, it will be customary to pass the shackle of a pad-

lock through the staple in a manner well understood. Then in order to unlock the hasp, the padlock would be disconnected from the staple 18 and the locking section 5 would be swung upon its pivot so as to disengage the staple from the slot 16. The locking plate is then pulled outwardly so as to cause its hinged connection with the intermediate section 8 to move away from the 10 door frame so as to disengage the curved extension 19 from the hinge connection and the aperture 15 in the intermediate plate 8. The door would then be unlocked and could readily swing away from the frame 6. The 15 hasp sections could then be swung to be arranged in overlapping relationship to one another and in close proximity to the door frame. If it is desired to lock the door in a closed position, the operation is simply 20 reversed. It will be also noted that due to the construction of the invention the hasp may readily be folded and positioned upon the locking element 17 as shown in Fig. 2, whereby the device will occupy a minimum 25 amount of space when being shipped or stored. In cases where it is merely desired to hook the door, instead of locking it, the locking plate 9 may be used as a handle for engaging the hook 19 with the opening 15 30 in the intermediate plate or section, so that it is not necessary to cause the staple 18 to pass through the locking plate 9 and use a padlock for fastening the door. It will therefore be obvious that the locking members 35 may be used either jointly for locking the door or separately for merely hooking the door in a closed position.

The foregoing description and the drawing has reference to the preferred or approved embodiment of my invention. It 40 is to be understood that such changes may be made in construction and arrangement of parts, materials, dimensions, etc., as may prove expedient and fall within the scope 45 of the appended claims.

Having thus described my invention what I claim as new and desire to secure by Letters Patent is:—

1. A device of the class described, comprising in combination, a hasp, and a pair 50 of locking members adapted for either joint or separate engagement with the hasp.
2. A device of the class described, comprising in combination, a hasp including 55 a pair of sections adapted to be arranged

at right angles to each other when in a locked position, and means engageable with the hasp at two points for co-operative engagement with the hasp for locking the same, or for separate engagement with the 60 hasp for hooking the same.

3. A device of the class described, comprising in combination, a hasp including a locking plate, and means engaging said plate adjacent opposite ends thereof for 65 locking the same.

4. A device of the class described, comprising in combination, a hasp, comprising a pair of sections each having an opening therein, and means adapted to project 70 through the openings when the sections are disposed at right angles.

5. A device of the class described, comprising in combination, a hasp, including a pair of hinged sections each having an 75 opening therein and adapted to be arranged at right angles to one another when in a locked position, and means adapted for either joint co-operation with the openings, or for separate co-operation with one open- 80 ing in one section.

6. A device of the class described, comprising in combination, a hasp, including a pair of hinged sections each having an opening 85 therein, one opening being contiguous to the connection between the sections, and means engageable with the opening when the sections are angularly disposed.

7. A device of the class described, comprising in combination, a hasp having a pair of openings therein, a hook and a staple adapted to extend through said openings to lock the hasp.

8. A device of the class described, comprising in combination, a hasp comprising a pair of hinged sections, one section having an opening therein, and the other section having an opening therein contiguous to the connection between the sections, and a pair of locking members adapted for co-operation with the openings, one of said members adapted to overlap the hinged connection between the sections.

In testimony whereof I affix my signature 105 in presence of two witnesses.

GEORGE S. OLSON.
